METAL WEATHER STRIP

Walter H. Storck, Nashville, Ill.

Application June 13, 1934, Serial No. 730,486

2 Claims. (Cl. 20—69)

The invention relates to weather strips and particularly for application to sliding sash windows, and has for its principal object the provision of a weather strip structure that is extremely efficient in preventing the entrance of cold air into the building, that is reasonable in cost of manufacture, and that is extremely efficient in operation and easy to install.

A further object of the invention is the provision of a weather strip structure including a casing adapted to be secured to the upright sides of a window frame, and to take the place of the parting bead between the upper and lower sash, and having spring actuated bars mounted therein and engaged by flanged strips on the upper and lower sash that hold the bars inwardly of the casing against the resistance of the resilient member behind each bar, provision being made as a part of the casing to hold the bars within the casing when the sashes are removed from the frame.

A further object of the invention is the provision of a dust pad mounted in the casing adapted to be secured to the meeting rail of one of the sashes, including a spring actuated member carrying a block of felt or other material to close the space between the upright bars of the weather strip hereinbefore referred to.

The invention will be described in detail hereinafter and will be found illustrated in the accompanying drawing, in which

Figure 1 is a view in elevation, partly broken away and shown in section of a window frame and sashes showing the improved weather strip structure mounted therein,

Figure 2 is a transverse sectional view on a plane indicated by the line 2—2 of Figure 1,

Figure 3 is a horizontal sectional view on a plane indicated by the line 3—3 of Figure 1, and

Figure 4 is a sectional detail on a plane indicated by the line 4—4 of Figure 3.

In the drawing similar reference characters are used to designate corresponding parts in all of the views.

In the drawing 10 designates side members of a window frame in which are mounted the upper and lower sashes 11 and 12, respectively.

Secured between the upper and lower sashes 11 and 12 to the side members 10 are the weather strip members, said members 10 being provided with a vertical groove 13 in which the weather strip member is secured. The weather strip member comprises a casing made preferably of sheet metal and having side members 14 with outward-

ly bent and returned portions 15 to receive driven fastenings for securing the casing to the members 10. The casings are also provided with partitions 16 formed by bending the sheet metal intermediate of its side edges as shown at 17 and then inwardly toward one another as shown at 18 and extended to form the partitions 16, the parts 18 providing shoulders for the purpose hereinafter stated. The partitions 16 with the side members 14 provide chambers 19 on opposite sides of the partitions in which are slidably mounted bars 20 having offset portions 21 that engage the shoulders 18 to limit the outward movement of the bars by the action of the leaf springs 22, said leaf springs being secured to the bars 20 intermediate of their ends by means of the driven fastenings 23.

Secured to each of the sashes 11 and 12 are strips 24 of sheet metal and having a flange 25 thereon that is preferably curved as shown to engage the curved outer edge of the bars 20, said flanges 25 having the bars inwardly of the shoulders 18 and against the action of the springs 22, and providing an airtight and weather-tight fit forming a weather seal between the sashes 11 and 12 and the window frame.

By this construction it will be apparent that the window sashes may be raised and lowered as desired and the weather seal will be effective.

It will be furthermore apparent that the casing including the side walls 14 provide a parting bead between the upper and lower sashes.

In order to close the opening formed to receive the partition 16 and its T-shaped end including the portion 17 and the shoulders 18, I provide a dust pad to be secured to the meeting rail of either the upper or the lower sash, comprising a casing 26 having a foot piece 27 adapted to be secured to a meeting rail by driven fastenings 28, and mounted in said casing is a plunger 29 preferably made of sheet metal bent into U-shape and engaging a pad 30 of felt or other suitable material that wipes the member 17. Casing 26 has an inturned projection 31, and the plunger has an outturned projection 32, and 33 designates an expandable coil spring terminally engaging said projection and functioning to hold the wiping member 30 in engagement with the part 17.

I claim as my invention:

1. A weather strip assembly for sliding sash window structures, comprising a casing to be secured to a window frame, a partition in said casing dividing it into two chambers, a bar slidably mounted in each chamber, spring means secured to each bar to normally project the bar

outwardly of the casing, and strips to be secured to upper and lower sashes in said frame, and flanges on said strips engaging the outer edge of the bars.

5 2. A weather strip assembly for sliding sash window structures, comprising a casing to be secured to a window frame, a partition T-shaped in cross section dividing the casing into two cham-

bers, bars slidably mounted in said chambers and having shoulders to engage the flanges on said partition, leaf springs secured to said bars to normally project outwardly of the chambers, strips to be secured to window sashes, and flanges on said strips engaging the outer edges of said bars.

WALTER H. STORCK.
